Primary Examiner — Katie Jane Stofko(74) *Attorney, Agent, or Firm* — Jordan IP Law, LLC; John L. Crimmins, Esq.(57) **CLAIM**

The ornamental design for a cereal food piece with emoji, as shown and described.

DESCRIPTION

FIG. 1 is a front, top and left side perspective view of a cereal food piece with emoji showing our design;

FIG. 2 is a front elevational view thereof;

FIG. 3 is a rear elevational view thereof;

FIG. 4 is a right side elevational view thereof, the left side elevational view being a mirror image thereof;

FIG. 5 is a top plan view thereof, the bottom plan view being a mirror image thereof; and,

FIG. 6 is a front, bottom and right side perspective view thereof, shown in an environment of use.

The less concentrated stippled shading and more concentrated stippled shading areas shown in FIGS. 1-6 represent contrasting appearances. The dot-dash-dot lines in Figures 1-6 illustrate the boundary of the invention and form no part of the claimed design. The broken lines in FIG. 6, depicting a bowl with an abundance of cereal food pieces and a spoon supporting a cereal food piece with emoji of our design, illustrate environment that form no part of the claimed design.
